UNITED STATES PATENT OFFICE.

CHARLES R. BIRDSEY, OF HINSDALE, ILLINOIS, ASSIGNOR, BY MESNE ASSIGNMENTS, TO UNITED STATES GYPSUM COMPANY, OF CHICAGO, ILLINOIS, A CORPORATION OF ILLINOIS.

PLASTER BOARD.

Application filed January 2, 1920. Serial No. 348,943.

To all whom it may concern:

Be it known that I, CHARLES R. BIRDSEY, a citizen of the United States, residing at Hinsdale, in the county of DuPage and 5 State of Illinois, have invented certain new and useful Improvements in Plaster Board (case E), of which the following is a description.

My invention belongs to that general class 10 of devices known as plaster board or the like, and relates particularly to an improved board which will be simple, substantial, durable, satisfactory and efficient, and which may be economically and accurately manufactured. The invention relates 15 particularly to a type of board in which the enclosed plaster, plaster Paris or equivalent plastic material is substantially enclosed on one or on both opposite edges, 20 and in which the edges are perfectly formed to conform to a definite specification as to size or angle. Many other objects and advantages of the construction herein shown and described will be obvious to those skilled 25 in the art from the disclosures herein given.

To this end my invention consists in the novel construction, arrangement and combination of parts herein shown and described, and more particularly pointed out in the 30 claims.

In the drawings, wherein like reference characters indicate like or corresponding parts,

Figure 1 is a sectional view through a portion 35 of the plaster board embodying the invention;

Figure 2 is a perspective view of a portion of the board;

Figure 3 is a sectional view through a portion 40 of a board illustrating a slight modification;

Figure 4 is a perspective view of a slightly modified construction, and

Figure 5 is a sectional view of another 45 modified construction.

Referring to the drawings, 1 represents a body of suitable material, as for example, plaster, plaster Paris or any equivalent suitable for the purpose, preferably such as may 50 be handled in a plastic state and thereafter allowed to set or harden. As shown, the body 1 is enclosed between the covering sheets 2 and 3 on the faces and the edges enclosed by the covering sheet portions 4. In 55 this type of board, the covering sheet 2 is

wrapped or folded over the body, enclosing the faces and edges, the same, however, being preferably first scored as at 6 before completely folding so as to produce a finished edge. The covering sheet may be of any 60 suitable material, and it may be mentioned that I have found paper of the desired weight or thickness very satisfactory for the purpose.

The sheet is preferably of such width that 65 the two edges will extend substantially close together, as indicated at 5, or they may overlap as shown in Figure 5. If desired, a strip 7 may be arranged over the meeting edges, substantially securing the two edges together. 70 The strip 7 may be of suitable material and secured in place in any desired manner. Ordinarily where the body is made up of any of the materials mentioned, enough of the material will be pressed 75 through between the edges and serve as a seal securing the strip 7 in place. The edges may be spaced a desired distance to permit the desired amount of material to escape, the amount of material required depending 80 upon the width of the strip. In Figure 3, I have shown how the strip 8 may be pressed down flush with the main portion of the face of the board, the same depressing the meeting edges 9 and 10, substantially as shown 85 or in any equivalent manner.

The construction shown in Figure 4 is substantially similar, except that a strip is arranged on the body at the interior of the covering sheet. Referring to this figure, 11 90 represents the body and 12 a sheet which is folded over to provide a cover sheet 13. The connecting portion 14 encloses the edges of the board or body, it being understood that the same may be scored as at 16 if so 95 desired. In this case, a strip 17 is positioned and the edges 15 then pressed in or down so that the face of the board is smooth. The edges may be secured to the strip in any desired manner, ordinarily sufficient material 100 flowing between the strip 17 and the edges of the sheet serves as a seal and secures the parts together. In the construction shown in Figure 5, the sheet 18 is wrapped over the edges, one edge portion, 105 19 overlying the other edge 20. It will be noted that with all of these constructions, the edge is substantially completely enclosed at both sides and edges. The resulting product is produced with a 110

straight, smooth edge and at a perfect angle, the board being uniform in width throughout its length. The completed product has many advantages, and it has increased strength and durability, and an improved appearance. In case of handling, the edges are protected and there is no sifting out or powdering of the body at the edge.

10 Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

15 What I claim as new and desire to secure by Letters Patent is:

20 1. A plaster board comprising a body, a cover sheet extending over one face of the body and folded over the edges onto the opposite side of the body with the edges of the sheet adjacent each other, and a sealing strip arranged over said body at the junctures of said edges on the exterior of the cover sheet.

25 2. A plaster board comprising a body, a cover sheet extending over one face of the body and folded over the edges onto the op-

posite side of the body with the edges adjacent each other, and a sealing strip arranged over and secured to said sheet at the junctures of said edges on the exterior of the cover sheet and depressed to substantially flush with the main portion of the face of the board.

3. A plaster board comprising a body, a cover sheet extending over one face of the body and folded over the edges onto the opposite side of the body with the edges of the sheet adjacent each other, and a sealing strip arranged in overlapping relation with the adjacent edge portions of the sheet.

4. A plaster board comprising a body, a cover sheet extending over one face of the body and folded over the edges onto the opposite side of the body, with the edges of the sheet adjacent to but separated from each other, and a sealing strip arranged over said body in overlapping relation with the adjacent edge portion of the sheet.

In testimony whereof, I have hereunto signed my name in the presence of two subscribing witnesses.

CHARLES R. BIRDSEY.
